Attorney.

UNITED STATES PATENT OFFICE.

OLIVER AUGUSTUS ALEXANDER, OF SAN FRANCISCO, CALIFORNIA.

OPEN FIRE-DOOR FOR FURNACES.

SPECIFICATION forming part of Letters Patent No. 632,615, dated September 5, 1899.

Application filed March 30, 1899. Serial No. 711,125. (No model.)

To all whom it may concern:

Be it known that I, OLIVER AUGUSTUS ALEXANDER, a citizen of the United States, residing at San Francisco, in the county of San Francisco and State of California, have invented a certain new and useful Improvement in Open Fire-Doors for Furnaces, of which the following is a full, clear, and exact description.

This invention relates to doors for furnaces, 10 and more especially to doors of the kind forming the subject of Patent No. 329,603, granted November 3, 1885, to Andrew J. Stevens, and which doors are designed primarily for locomotive-boiler furnaces; and the object of the 15 invention is to provide for the more convenient feeding and economical combustion of the fuel.

In carrying out my invention I provide the main door with a supplemental door, through 20 which latter the fuel may be fed without opening the main door, and adjacent to this supplemental door I arrange a deflector plate or shield which may be readily put in position and removed, and which also may be adjusted 25 as to inclination so as to direct the inflowing air in order to conserve the fire and protect the boiler against the inrushing of large volumes of cold air, all as I will proceed now more particularly to set forth and finally claim.

30 In the accompanying drawings illustrating my invention, in the several figures of which like parts are similarly designated, Figure 1 is a front elevation. Fig. 2 is a top plan view. Fig. 3 is a vertical section, taken substantially 35 in the plane of line 3 3, Fig. 1, and showing in dotted lines the plate or shield in or about the position shown in Fig. 4, and also showing in dotted lines the supplemental door opened. Fig. 4 is a vertical section, taken substantially 40 in the plane of line 4 4, Fig. 1.

a may represent a portion of a furnace, and *b* is the door hinged thereto at *c* and provided with a latch and keeper *d*, all of approved construction. The door *b* is provided with the 45 supplemental door *e*, hinged thereto at *f* and adapted to open outwardly, as indicated by dotted lines in Fig. 3, so as to uncover an opening *g* in the main door through which the fuel may be fed without opening the main door.

50 On opposite sides of this opening *g* and on the door *b* are constructed the open sockets *h h*. *i* is a plate or shield of metal having the lat-

erally-extended journals *k*, which find bearings in the sockets *h* when the said plate or shield is inserted through the opening *g* of the door *b*, so that the said plate or shield may be given a rocking motion in the said sockets as in bearings. An arm *l* projects upwardly from one side of the plate or shield *i*, and in the path of movement of said arm *l* is arranged an 60 adjusting device *m* of any approved construction and preferably, as herein shown, consisting of a T-headed screw, which is adjustably supported in a bracket *n* made fast to any appropriate stationary part of the furnace. This 65 screw may be adjusted in the direction of its length in said bracket, and, if necessary, may be held in such adjustment by a set-screw or jam-nut *o*. As will be seen by comparison of Figs. 3 and 4, the angle of inclination of the 70 shield or plate may be varied by running out and in the adjusting device *m*, and thereby the incoming air may be distributed more or less widely over the surface of the fire.

My invention differs from prior inventions, 75 in that the plate or shield may be readily removed without detaching any portion of the door and without detaching any support for the said plate, and also in the fact that the said plate may be readily adjusted to vary its 80 angle of inclination, and also in the fact that as the door is open the plate or shield parts from its adjusting device and falls against the door clear of the mouth of the furnace. Obviously when not desired the shield or plate 85 may be wholly removed without in any wise dismantling the door or its appurtenances.

The door may be supplied also with a protecting-shield or fire-shield *p* and with a series 90 of constant or regulated air-inlets *r*.

Obviously my invention may be applied to doors already in use by affixing thereto suitable bearings to receive the shield and by attaching to some fixed portion of the furnace the adjusting device.

I do not limit my invention to the exact details of construction, but esteem as within my invention such variations as will accomplish the ready application and removal of the plate or shield and its adjustment as to inclination 100 within the fire-box or combustion-chamber.

The use of shields of the character herein described has demonstrated their capacity to reduce the quantity of smoke due to imper-

fect combustion and also to enable the fireman to control his fire.

What I claim is—

1. A furnace-door, provided with bearings, 5 a deflector plate or shield arranged in said bearings, an arm projecting from said plate, and an adjusting device fixed beyond the door and coöperating with said arm to vary the angle of inclination of the plate or shield and 10 release said shield when the door is swung open, substantially as described.
2. A furnace-door, provided with a supplemental feed-door, a shield pivoted to the main door within the opening for the supplemental 15 door, an arm projecting from said plate or shield, and a T-shaped set-screw arranged on a fixed portion of the furnace and in the path of movement of said arm and adjustable to vary the angle of inclination of the plate or 20 shield, substantially as described.
3. A furnace-door, provided with a supplemental feed-door, open sockets arranged upon

opposite sides of said door-opening, a deflector plate or shield having laterally-extended journals to engage said sockets as bearings, 25 the plate or shield projecting into the furnace or fire-box through said supplemental door-opening, an arm projecting from said plate or shield upwardly, a T-shaped set-screw and a bracket therefor secured remotely from the 30 door, the said set-screw being arranged in the path of movement of said arm and adjustable to vary the angle of inclination of the plate or shield, the shield being bodily removable from its bearings and thus detachable from 35 the door without dismantling the door or its appurtenances, substantially as described.

In testimony whereof I have hereunto set my hand this 27th day of March, A. D. 1899.

OLIVER AUGUSTUS ALEXANDER.
